UNITED STATES PATENT OFFICE.

HOWARD W. LESTER, OF HARTFORD, CONNECTICUT.

LAMP.

1,401,415.

Specification of Letters Patent. Patented Dec. 27, 1921.

Application filed January 20, 1920. Serial No. 352,647.

To all whom it may concern:

Be it known that HOWARD W. LESTER, a citizen of the United States, residing at Hartford, in the county of Hartford and 5 State of Connecticut, has invented certain new and useful Improvements in Lamps, of which the following is a specification.

This invention relates to lamps. A lamp involving the invention is of course capable 10 of general use although it is of especial utility when employed in connection with an automobile. It can be employed for instance in this event as a head-light. It may of course be used with equal utility in 15 connection with a boat or a ship and in many other ways. The primary purpose I have is the provision of means of the character set forth by which rays from a lamp or lamps may be intensely projected without 20 the so-called glare. The article may be inexpensively and easily produced.

In the drawings accompanying and forming a part of the present specification I have shown in detail several of the many 25 ways of carrying the invention into effect, which will be set forth fully in the following description to enable those skilled in the art to practice the same. Clearly I am not restricted to this disclosure. I may de- 30 part therefrom in several respects within the scope of the invention defined by the claim following said description.

Referring to said drawings:

Figure 1 is a cross section of one form 35 of the lamp.

Fig. 2 is a front elevation of the same.

Fig. 3 is a view corresponding to Fig. 1 of a second form of the article.

Fig. 4 is a view from the front with a 40 part broken away and in section of the lamp of Fig. 3.

Like characters refer to like parts throughout the several views.

Referring first to Figs. 1 and 2, the device therein shown, involves in its make-up, what may be broadly considered a body or casing such as that denoted in a general way by 2 and which can be formed from sheet metal or any other proper stock. This 45 body or casing 2 comprises what might be considered a back as 3 and an overhanging compound curved top as 4, the back in fact being shown as arched, curved or bowed. From the lower portion of the back 3 ex- 50 tends forwardly the bottom 5 from the front of which extends upwardly the flange or lip 6. The bottom 5 is not necessarily flat but 55 may be as shown of somewhat compound curvature. This casing 2 may be covered at its sides by the closures, plates or disks 60 7 suitably fastened to the body. The casing 2 in turn may be supported by a post as 8 rigidly connected in some convenient way to the under side thereof.

The casing constitutes a suitable support 65 for one or more illuminants such as lamps 9. These lamps may be of any desirable character although they desirably consist of bulbs. When electric bulbs 9 are used they may be connected in some convenient 70 manner to a source of electric supply. Back of them and adjacent the flange or lip 6 is arranged a reflector 10 which may be of glass, metal or of composite character. This reflector 10 obviously intensifies the rays 75 projected by the lamps or lamp 9. The space or interval between the lower or forward edge of the arch top 4 and the edge of the inwardly curved portion of the flange 6 presents an opening 11 through which the 80 rays from the lamps, or it might be one lamp, are projected. The rays are generally delivered downward by the construction 85 hereinafter described.

Set in the space in the back 3 below the 85 top 4 is a second reflector such as the mirror 12. It is not necessary that this reflector or mirror should be of glass for it might be of metal or of suitable composition. It is ar- 90 ranged at an inclination to the vertical, the incline being downwardly and backwardly from the upper edge thereof. This reflector or mirror 12 is rigidly held in place to the back 3 between closing plates 7 and it re- 95 ceives upon it the rays projected from a lamp or lamps 9 and the reflector 10 these rays in turn being delivered downwardly through the opening or slot 11. The flange or lip 6 acts as a positive barrier to prevent one in front of the device from receiving 100 directly the rays from the lamp or lamps 9, these rays as I have noted being delivered upon the mirror or reflector 12 and in turn delivered downwardly so that one observing the structure from the front experiences no 105 ill effect. The two light bulbs 9 are fitted in sockets 13 which extend through openings in the bottom of the casing 3 and are connected to the hollow bar 14 through which the leads 15 connected to the respective 110 lamps or bulbs 9 extend.

When the lamps or bulbs 9 are on, the rays

therefrom are projected onto the reflector 10 and by the latter are directed against the face of the reflector 12 and are finally projected through the opening 11 at the front of 5 the casing.

In Figs. 3 and 4 I show one of the many other forms of the device and parts in this which correspond to that shown in Figs. 1 and 2 will bear similar characters with 10 prime marks. In this construction there is but a single lamp 9' supported at its ends by brackets 16 in the channel 17 near the ends thereof. The leads 15' of this lamp 9' extend through the tube 14' and are connected 15 with the ends of the lamp.

In the modified construction there is but a single reflector the rays of light being intensified by a suitable lens or lens means because the lens means may be entirely different from that shown. There is but a single 20 lens illustrated, it being denoted by 18 and being disposed longitudinally of the casing 3' and connected for instance by bolts 19 to the ends 7' of the casing. This lens 18 is at 25 a slant as shown and is between the lamp 9' and the reflector 12' which is a duplicate of the reflector 12. The rays of light emanating from the lamp 9' pass through the lens

18 and then onto the reflector 12' and subsequently through the front opening 11', the 30 flange 6' of course covering the lamp 9' and the lens 18 for that matter from the front of the casing 3'.

What I claim is:

A lamp comprising a casing having a light 35 opening, a reflector in the back of the casing, to project rays through said light opening, a reflector in the casing to receive rays from a lamp and which are projected thereby onto the other reflector, a hollow bar for conductors mounted below the casing, lamp sockets in the casing at the base of and back of the second reflector, the sockets being adapted to receive the said conductors for connection with the lamp, the forward lower side of the 40 casing being curled upwardly and rearwardly to cover the lamp from the front of the casing, the latter being curled upwardly and forwardly beyond the lower portion thereof. 50

In testimony whereof I affix my signature in the presence of two witnesses.

HOWARD W. LESTER.
